[57] CLAIM

The ornamental design for a combined key storage stand and carrier, as shown and described.

DESCRIPTION

FIG. 1 is a front elevational view of a combined key storage stand and carrier showing my new design;

FIG. 2 is a top plan view thereof;

FIG. 3 is a side elevational view the opposite side being a mirror image;

FIG. 4 is a cross-sectional view taken along line 4—4 of FIG. 1;

FIG. 5 is a bottom plan view thereof;

FIG. 6 is a sectional view taken along line 6—6 of FIG. 1; and

FIG. 7 is a sectional view taken along line 7—7 of FIG. 1.

The legs of the stand are in folded position for carrying.
